DEVICE FOR GUIDING THIN FILM BANDS

Johannes Adrianus Haringx, Eindhoven, Netherlands, assignor to Hartford National Bank and Trust Company, Hartford, Conn., as trustee

Application July 3, 1946, Serial No. 681,390
In the Netherlands September 30, 1943

Section 1, Public Law 690, August 8, 1946
Patent expires September 30, 1963

3 Claims. (Cl. 271—2.6)

1

This invention relates to a device for guiding a thin film band, for example, a very thin film made from cellophane.

The customary devices for guiding film bands which, for example, are perforated and are moved by means of toothed rollers, or sometimes are guided via an untoothed roller between two flanges, have in the case of these very thin films the drawback that the material cannot sustain it so that damage and even breakage are unavoidable. More particularly when the film is in a damp condition, which often occurs when it is being worked up, this drawback is experienced to a high extent.

According to the invention, this drawback is obviated by compelling the film band at the place of the guiding member to engage a stop by one of its sides by driving and/or braking the said band to a greater degree on one side thereof with respect to the longitudinal axis thereof, than on the other side thereof, said stop being located in the proximity of the guiding member. This guiding member may be a rotating or stationary roller or a stationary film track. Due to the film band being driven and/or braked unsymmetrically as described above, a force couple is exerted on the film in the plane of the latter so that the film experiences a resultant lateral force and moves sideways so as to engage the stop. This lateral force can be accurately adjusted to any desired value by the choice of the forces for driving and/or braking. Perforation of the film is not necessary, whilst the single stop is sufficient to guide the film. As the force with which the film is pushed against the stop may be very small, any damage to the film and even the formation of a so-called "foot," i. e. curling up of the strip on the side of the stop, are thus avoided.

In order that the invention may be clearly understood and readily carried into effect, it will now be explained more fully with reference to the accompanying drawing, in which, by way of example, a few forms of construction are represented.

Figs. 1 and 2 represent diagrammatically a bottom and a lateral view respectively, of a device in which the film is substantially braked unsymmetrically.

Fig. 1a represents diagrammatically a bottom view of another form of roller which may be used.

Figs. 3 and 4 represent diagrammatically a bottom and lateral view, respectively, of a device wherein the film is braked and driven unsymmetrically.

2

Figs. 5 and 6 represent diagrammatically a bottom and lateral view, respectively, of a further device in which unsymmetrical braking takes place.

In Fig. 1, 1 designates a film band which runs on a roller 2. In Figs. 1 and 2 this roller is a guide roller which moves along with the film. In Figs. 1, 2, 3 and 4 two small felt plates 3 and 4 are provided unsymmetrically with respect to the longitudinal axis of the film, the film band running between them. These plates may be pressed more or less strongly against one another, which pressure can be adjusted at will with the aid of a device (not shown). Due to the friction between these plates and the film band, a resultant force is exerted on the film in the plane of the latter, so that the film engages a stop 5. This is promoted, for example, by the fact that the film is not supported throughout the whole width by the roller 2 (cf. Fig. 1a) which results in itself already in a more or less unsymmetrical drive.

With the device according to Figs. 3 and 4 the said resultant force is further increased owing to the film being also unsymmetrically driven, for the roller 2 is here a driving roller, whilst a pressure roller 6, which engages unsymmetrically only part of the driving roller 2 in the axial direction, ensures that the film cannot slip at this point. This results in that an additional force is exerted on the film unsymmetrically with respect to the axis of the latter, which force moves the film forward. If the pressure exerted by the film on the stop is still so great that the film curls up on its side and thus still forms a "foot," it is advisable to provide the stop in such a manner that the film always engages the latter with its curved portion, as is shown in Figs. 3 and 4.

Figs. 5 and 6 show another possible embodiment of the invention. Here the film is guided over a piece of felt 7 cut off obliquely. The roller may also be stationary, in which event the piece of felt 7 may be fastened to this roller. Here again we obtain an unsymmetrical friction which compels the film to engage the stop. The latter form of construction can only be used if before the roller 2 the film band has a sufficient free length so that a smaller angular displacement is sufficient to cause it to engage the stop since in this case the frictional force is much smaller than in the above-mentioned forms of construction and consequently the film experiences a smaller force which pushes it against the stop. In the latter form of construction the engagement of the stop by the film is favoured by the fact that the latter is compelled to slide over an oblique surface, so that, so to speak, it slides against the stop. This

takes place more particularly when the film is moreover arranged vertically, so that also the weight of the film contributes thereto.

As a matter of course the invention is not confined to the above-mentioned forms of construction given, by way of example, but it also includes a device in which the film, when guided in accordance with the invention, is simultaneously wound, for example, on a spool.

What I claim is:

1. A device for guiding a thin film band comprising a roller over which the band passes for changing the direction thereof, a stationary plate element adjacent said roller and following the contour thereof for a part of the circumference of said roller, said plate element having an edge which is transverse the direction of travel of the band cut off obliquely with respect to the axis of said roller so that the shape of said plate element in effect diminishes in a direction toward one side of said roller and a stop located beside said roller and said plate element at said one side of said roller.

10

2. A device for guiding a thin film band as claimed in claim 1 wherein said plate element comprises a sheet of felt.

3. A device for guiding a thin film band as claimed in claim 1 wherein said stop located beside said roller and said plate element at said one side of said roller is further arranged so that a curved portion of the band traversing the plate element and roller will make contact therewith.
